UNITED STATES PATENT OFFICE.

WILLIAM GEORGE AYRE, OF BAKER, AND FREDERICK LENNARD SHAW, OF DURKEE,
OREGON.

INSULATOR.

1,200,294.

Specification of Letters Patent.

Patented Oct. 3, 1916.

Application filed January 9, 1914. Serial No. 811,281.

To all whom it may concern:

Be it known that we, WILLIAM GEORGE AYRE and FREDERICK LENNARD SHAW, citizens of the United States, residing at Baker and Durkee, respectively, in the county of Baker and State of Oregon, have invented certain new and useful Improvements in Insulators, and do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to insulators for electric wires such as are commonly employed for the transmission of electrical currents and is what may be termed a self locking tieless insulator in that the wire is automatically locked within the insulator and requires no tying or fastening thereto as is usually employed in devices of this character, and also prevents the insulator from unscrewing, while the construction of the insulator provides for a free sliding movement of the wire, as is frequently advantageous in running and constructing the lines.

The construction of the initial wire groove or passage in the insulator provides for ready insertion of the wire into the insulator while the wire is in a taut or tightly strung condition as no bends or curves in the wire are necessary for its initial application to the insulator.

In the use of this insulator the wire has a free sliding movement so as to accommodate itself to expansion and contraction without straining the insulator or the post or other support to which the same is attached.

By the use of this device, untying and re-tying of wires to the insulators in the event of repairing the line is entirely eliminated.

By the use of insulators constructed in accordance with this invention a single line-man can in most instances handle the line without assistance and can attach and detach the same from the insulators.

The invention consists in the novel construction of the insulator which provides for automatically locking the line in proper position within the insulator and thereby

dispose of the usual tying and fastening usually needed in insulators of this character.

The invention consists in certain novel features of construction all of which will be first fully described and afterward specifically pointed out in the appended claims.

Referring to the accompanying drawing: Figure 1 is an elevation of an insulator constructed in accordance with this invention. Fig. 2 is a vertical sectional view through the same. Fig. 3 is a transverse sectional view taken on line 3—3 of Fig. 2. Fig. 4 is a transverse sectional view taken on line 4—4 of Fig. 2, and Fig. 5 is an elevation illustrating the insulator formed in a slightly different shape in which the wire is received from the bottom thereof.

Like numerals of reference indicate the same parts throughout the several figures in which—

1 indicates the insulator which may be formed as shown in Fig. 1 or formed as shown in Fig. 5, it being clearly understood that the external form of the insulator is immaterial as far as this invention is concerned, as is also the method of hanging or supporting the same as the insulator may be so constructed and arranged that it may receive the wire from any part thereof.

Referring now to the drawing it will be seen that the insulator is provided with a deep and straight slot 2 which enters the same in the manner as shown, it being essential that the initial opening or slot 2 be straight and arranged in line with the wire.

Upon one side of the insulator there is formed a convexed projection 3 while upon the opposite side of the slot and directly opposite the said convexed projection 3 there is arranged a concaved recess 4, said convexed projection 3 and concaved recess 4 being curved in cross section as shown in Fig. 3. The convexed projection 3 terminates at the point 5, the insulator being undercut at this point to the point 6 so as to provide a straight groove or channel 7 transversely of the insulator; while it will be seen from Fig. 4 that the wall 8 of the channel passage 7 is curved or flared outwardly at the end 9 while the wall 10 of said channel or passage 7 is curved or flared outwardly at the end 11.

From an inspection of Fig. 1 it will be seen that the convexed projection 3 extends 110

entirely across the channel 7 in such manner as to prevent a wire from passing upwardly out of the channel 7 into the slot 2 when the said wire is in a straight or taut position.

As will appear from Fig. 1 a threaded recess 12 is provided in the bottom of the insulator to connect the same to a suitable support, while in Fig. 5 the said threaded recess 12 is shown in dotted lines in which latter figure the position of the wire receiving and locking arrangement is arranged to receive the wire from the bottom of the insulator.

Having thus fully described the construction of this invention its operation is as follows: The insulator being formed as shown in the accompanying drawing the wire is passed into the deep and straight slot 2 until it engages the convexed projection 3. The advantages of the deep and straight construction of the initial slot 2 is that in the application of taut or tightly strung wires, said taut or tightly strung wires will readily enter the deep and straight initial slot 2 without first having to impart to the wire any bend or curve. The wire being taut and flexible a slight curvature or bend is imparted to the wire upon passing out of the deep straight initial slot 2 by reason of the gradual rounded form of the convexed projection 3, the wire being forced at this point into the concaved recess 4 of the insulator and progresses inwardly in this position until it reaches the bottom of the convexed projection 3 at which point it drops into the transverse channel 7 and underneath the convexed projection 3. When in this position the wire is securely and permanently locked within the channel 7, it being a matter of physical impossibility to remove the wire while the same is lying in a straight lined position within the wire receiving channel 7, while the wire cannot be removed from the channel 7 accidentally and while in a tight and operative position the same can readily be detached from the insulator whenever desired by curving the wire so as to enter the concaved recess 4 in the insulator in which

position it will be moved from under the convexed projection 3 and can be readily withdrawn from the slot 2.

Having thus fully described the invention it is apparent that certain immaterial changes and alterations can be made in the construction shown in the accompanying drawing, and we consider ourselves clearly entitled to all such changes and modifications as fall within the limit and scope of the appended claims.

What we claim as new and desire to secure by Letters Patent of the United States is:—

1. An insulator of the type described, having a line-wire receiving slot, said slot opening out through the upper end of said insulator, with its walls extending from said upper end downwardly in right or straight lines a certain distance, said slot-walls in continuation farther downwardly being curved upon convex and concave lines, respectively, with the convexity and concavity of said walls terminating inwardly short distances from the lateral outer surfaces of the insulator, the terminals of said walls at said points being produced upon straight or right lines, the inner ends of said slot-walls terminating in a right-angled undercut groove.

2. An insulator of the type described including a deep straight line-wire receiving slot having its walls extending from the outer surface of the insulator inwardly thereof in right or straight lines, said slot walls in continuation farther inwardly being curved upon convex and concave lines respectively to receive a wire from said right or straight line walls to impart a bend to the wire in conformity to the convex and concave wall portions, the inner ends of said slot-walls terminating in a right angled undercut groove.

In testimony whereof we affix our signatures in presence of two witnesses.

WILLIAM GEORGE AYRE.
FREDERICK LENNARD SHAW.
